(57) **CLAIM**

The ornamental design for a bottle, as shown and described.

DESCRIPTION

FIG. 1 is a front left three quarter perspective view of a bottle in accordance with my new design.

FIG. 2 is a front right three quarter perspective view of the bottle shown in FIG. 1;

FIG. 3 is a left side elevation view of the bottle shown in FIG. 1;

FIG. 4 is a right side elevation view of the bottle shown in FIG. 1;

FIG. 5 is a front elevation view of the bottle shown in FIG. 1;

FIG. 6 is a rear elevation view of the bottle shown in FIG. 1; and,

FIG. 7 is a top plan view of the bottle shown in FIG. 1. The broken lines in the drawings illustrate the portions of the bottle that form no part of the claimed design.
